CLAIM

The ornamental design for an incinerator toilet or the like, substantially as shown.

DESCRIPTION

FIG. 1 is a perspective view taken from the front, top and one side of an incinerator toilet or the like showing our new design;

FIG. 2 is a top plan view thereof;

FIG. 3 is a perspective view taken from the front, top and side opposite that shown in FIG. 1; and

FIG. 4 is a rear elevational view thereof.
